SELF-CLOSING DETACHABLE THEATER
SEATMilford T. Vandervoort, Grand Rapids, Mich.,
assignor to Ernest A. Wedemeier, Grand
Rapids, Mich.

Application June 5, 1933, Serial No. 674,321

5 Claims. (Cl. 155—85)

My invention relates generally to means whereby automatic return movement of a pivoted element is had, and more particularly to a folding chair seat construction.

5 In many chair installations, as in theaters and the like, it is desirable that the chair seats fold upwardly and remain in their upper or vertical positions when empty whereby the patrons may move about with a minimum of difficulty and 10 furthermore the sweeping and cleaning of the theater floor is facilitated as will be readily understood.

Also, in installations of this character, sometimes the floor is uneven thus causing irregularity in the positioning of the standards which, in turn, cause binding of the seat during its pivotal movement.

15 My invention eliminates both of the above difficulties. The spring lever arrangement beneath the seat initiates the upward movement of the seat and then, with diminishing effect, rotates the seat upwardly about its pivot. Near the upper arc of movement of the seat a snubbing device comes into effect and decelerates the seat to a very slow and gradual motion; this snubber continuing its action until the seat abuts against the back of the chair. The latter part of the motion is aided by the action of gravity upon the rear side of the seat's pivot.

20 The journals about which the seat turns may be enclosed by yieldable sleeves which permit both axial and radial movement of the seat thereon as well as some tilting movement and thus any irregular positioning of the standards 25 is taken care of.

Still another advantage resides in the spring adjusting means, this determining the upward force acting upon the seat. Also, the adjusting means is detachable to permit removal of the seat 30 from its standards.

In the drawings:—

Fig. 1 is a vertical cross sectional view through a chair seat construction made in accordance with my invention and showing the seat in its upper or folded position.

Fig. 2 is a plan view of several of the chair seats, the seats themselves being shown in dotted lines.

Fig. 3 is an enlarged view, partly in section, 50 particularly disclosing my novel hinge construction.

Fig. 4 is a view similar to Fig. 3 but showing the seat in its lowest or operative position.

Fig. 5 is a plan view of Fig. 4.

55 Fig. 6 is a fragmentary view of Fig. 5, the re-

cessed bearing block being not shown in order to clarify the disclosure.

Fig. 7 is a fragmentary view looking in the direction as indicated by the arrow A in Fig. 3.

Fig. 8 is a sectional view taken along the line 5 8—8 of Fig. 6.

Similar numerals refer to similar parts throughout the several views.

Referring particularly to Figs. 1 and 2, 10 indicates chair seat supporting standards on which 10 are mounted the arm rests 11 and backs 12. Brackets or plates 13 are attached to the standards, journals 14 being integrally formed with and extending from the several bracket members. See particularly Figs. 4 and 5. As shown 15 in Fig. 3, a seat cushion base 20 having a seat cushion 21, see Fig. 1, has a cast or stamped block 22 rigidly attached thereto, this block being recessed in semi-cylindrical shape as indicated at 23. Also, see Fig. 4, a slot 24 is formed at the 20 front end of the block. A bearing arm 25 is attached at 26 to the underside of the seat base and has a bearing portion 27 adapted to fit into the semi-cylindrical portion of the block member 22, a stud 28 extending through the bearing 25 arm and the slot 24 in the block to hold these members tightly against the underside of the seat. A channel member 30 is pivoted at 31 to the front end of the bearing arm and extends below the journal 14 as shown in Figs. 1, 3 and 4. 30

A boss 32 having a cam edge 33, is formed with a stop portion 34 extending forwardly from its lower end, has a flexible element 35 such as a leather strip entirely encircling the same, a rivet 36 joining the ends thereof. 35

A coiled spring 40, of the shape shown in Figs. 4 and 7, is detachably and adjustably fastened at 41 to the channel member 30 and its free ends are held together and joined by the clip 42. A loop member 43 partly encircles the bearing arm 40 45, see particularly Fig. 6, and a floating eye on the snubber member 44, preferably made of a flexible metal strip, pivotally connects the coiled spring 40 and the connecting loop 43 as clearly shown in Fig. 4. 45

The journal member 14, previously referred to, has an axial groove 15 therein. A flexible resilient sleeve 16, preferably formed of leather, encircles the journal 14 and a pin 17 having its head in the groove 15, extends outwardly through 50 the leather sleeve and prevents turning of the leather sleeve with respect to the journal member, thus preventing wear therebetween.

The bearing arm 25 has a slot 39 formed therein, the end of the pin 17 riding in the slot and 55

maintaining the leather sleeve in proper axial alignment with the bearing member 25.

The operation

5 When the parts are positioned as shown in Fig. 1 the center of gravity of the seat and its seat cushion lie to the left of the journal 14 and consequently the same tend to rotate counter clockwise. However, the snubber member 44, see
10 Fig. 3, is tensioned by being bent as this upward movement occurs and thus the movement is arrested in a gradual manner without noise. Also, the detrimental rubbing contact between the top of the seat cushion and the seat back is eliminated.
15

When one desires to use the seat, the same is pulled outwardly and downwardly whereupon the parts move toward the position shown in Fig. 3, the free end of the channel brace lever 30 riding
20 against the leather and preventing any noise. This elimination of noise is very desirable.

Further movement of the seat downwardly causes the free end of the channel member to travel along the cam or guiding edge of the boss
25 32 and forces the channel member 30 to rotate about its pivot 31, thus tensioning the coiled spring 40. Lastly, see Fig. 4, the end of the channel member 30 abuts against the stop member 34 and, after forcing the leather 35 against the stop
30 34, brings the seat to its proper lower position in which it is utilized.

Upon removal of the weight from the seat cushion, the spring 40 immediately becomes active and tends to pull the free end of the channel member 30 toward the journal member 14 and this movement causes a reaction between the free end of the channel member 30 and the cam edge 33 which in turn causes the seat to rotate upwardly.

40 After the seat has turned upwardly to approximately the position shown in Fig. 3, the free end of the channel member abuts against the leather sleeve 16 through the floating member 44 and, if desired, the upper end of the encircling strap member 35 and this causes an action which prevents rapid movement of the seat. That is, the member 44 is engaged between the journal 14 and the channel member 30 and thus the spring member 44 is gradually bent from substantially a straight line position as shown in Fig. 4 to a curved flexed position as shown in Fig. 1. Thus
45 the seat is brought to a gradual, noiseless stop.

50 From the above description, it will be understood that my invention as applied to a folding seat, will cause the same to move to its upper position in a positive but quiet manner.

I claim:

1. A construction of the class described, comprising, a standard having a journal extending therefrom, a seat, bearing means fastened to the underside of said seat, said bearing means having a recess therein, said recess receiving the said journal, an arm pivotally attached at one end to the said seat and extending downwardly at an angle thereto, a stop member located on the standard, the free end of the said arm abutting

against the stop member when the seat is in substantially horizontal position to prevent downward movement of the said seat, spring means mounted upon the seat and tending to pull the free end of the arm toward the said journal, and cam means fixed to an element of said standards and engaging the free end of said arm for guiding the free end of the said arm whereby the seat is moved to substantially vertical position due to the action of the said spring means.
10

2. In a device of the character described, a supporting standard having a journal extending therefrom, a seat member or the like adapted to be pivoted upon said journal, said seat member having a recess therein adapted to be placed 15 downwardly over said journal when the seat is horizontally located, an arm pivoted to the said seat and extending under the said journal, spring means tending to move the arm against the said journal and cam means for guiding the free end 20 of the said arm downwardly from the said journal when the seat is moved from the vertical position to a horizontal position and stop means adapted to prevent movement of the free end of the pivoted arm downwardly beyond a predetermined point for the purpose described.
25

3. In combination, two spaced apart standards having journal members extending therefrom, means to mount one edge of the seat upon one of said journal members and means to mount the 30 other edge of the seat upon the other of said journal members, said mounting means including a block member having a recess therein fitting approximately one-half of the said journal, an arm pivoted onto the seat and extending on the opposite side of the said journal, spring means tending to urge the arm against the said journal, said arm moving in a path on movement of the seat, and stationary means located in the path of the arm whereby movement of the seat 40 about its axis will cause the free end of the arm to move away from the said journal for the purpose described.

4. A construction of the class described comprising supporting standards having journal 45 members extending therefrom, a seat member pivoted upon said journal members, means for raising said seat member upon said journal members including an element pivotally connected to said seat member and having a portion movable 50 toward and away from one of said journals, means urging said movable portion toward said journal, cam means rigid with a supporting standard guiding said movable portion away from said journal as the seat is lowered about the journals, 55 and stop means to limit the movement of the movable portion away from the journal and to support the seat member in horizontal position.

5. The elements combined in claim 4 but also including spring means located between the movable portion and the journal, said spring means being engaged between the said movable means and the journal during the last of the movement of the seat to vertical position for the purpose described.
